UNITED STATES PATENT OFFICE.

CLEMENS G. BODUNGEN, OF LAGRANGE, TEXAS.

MOTE-BOARD FOR COTTON-GINS.

SPECIFICATION forming part of Letters Patent No. 758,166, dated April 26, 1904.

Application filed June 13, 1903. Serial No. 161,338. (No model.)

To all whom it may concern:

Be it known that I, CLEMENS G. BODUNGEN, a citizen of the United States, residing at La-
5 grange, in the county of Fayette and State of Texas, have invented a new and useful Mote-
Board for Cotton-Gins, of which the follow-
ing is a specification.

The invention relates to a mote-board for cotton-gins.

10 The object of the present invention is to improve the construction of cotton-gins, more especially the construction of the mote-board, and to provide a simple and comparatively inexpensive mote-board adapted to be readily applied at a small cost to cotton-gins of the ordinary construction without necessitating any material change in the construction thereof and capable of saving the nap-lint and motes usually lost and of conducting the same 15 to the cotton-seed conveyer.

A further object of the invention is to prevent motes and nap-lint from collecting under the gin stand or frame, where they are liable to take fire and destroy the cotton-gin and 20 from whence it is necessary to remove them by hand, which often results in the loss of a hand or an arm.

Another object of the invention is to prevent the updraft, which often interferes with 25 the operation of the brush-cylinder in opening the lint and separating therefrom the motes, nap, and trash and which often causes the motes, nap, and trash to be carried rearwardly through the flue or passage with the 30 lint.

Also it is the object of the invention to provide a mote-board which will cause a regular and proper draft from the front of the gin stand or frame to the brush and out through 40 the flue at the exit.

With these and other objects in view the invention consists in the construction and novel combination and arrangement of parts hereinafter fully described, illustrated in the 45 accompanying drawings, and pointed out in the claims hereto appended, it being understood that various changes in the form, proportion, size, and minor details of construction within the scope of the claims may be re-
50 sorted to without departing from the spirit or

sacrificing any of the advantages of the invention.

In the drawings, Figure 1 is a vertical section of a cotton-gin provided with a mote-board constructed in accordance with 55 this invention. Fig. 2 is a detail view of a portion of the mote-board.

Like numerals of reference designate corresponding parts in both figures of the drawings.

1 designates the frame or stand of the cotton-gin, which frame or stand is provided at the top of its front portion with the usual hopper or chamber 2 for the reception of the cotton. The gin frame or stand is of the 65 usual construction and is provided at the bottom and rear of the hopper or chamber 2 with gin-saw ribs 3, arranged at regular intervals and spaced apart to receive gin-saws 4, which are adapted to carry the fibers of lint from 70 the hopper or chamber 2 in the usual manner. The gin-saws 4 are mounted on a horizontal shaft or mandrel 5, and the lint is brushed from the saws by a rotary brush-cylinder 6, provided at its periphery with brushes 75 7 of the ordinary construction. The brush-cylinder 6 removes the lint from the saws and carries the same rearwardly and upwardly through the passage or flue 8, the motes, nap-lint, and sand dropping in front of mote-board 9 at 13.

The mote-board 9, which is constructed of sheet metal—such as zinc, galvanized steel, aluminium, or other suitable material—consists of a horizontal upper portion 10, located directly beneath the brush-cylinder 6 and preferably secured to the upper face of a horizontal board 11, constructed and arranged similar to the ordinary horizontal mote-board; but the improved mote-board may be supported 85 by any other suitable means, as will be readily understood. The mote-board 10 is angularly bent and extended downward at the front edge of the supporting-board 11, which is spaced from the front of the gin frame or stand to 95

provide a passage 12 for the falling motes, nap, sand, and other foreign matter. The angular bend 13 conforms to the configuration of the front edge of the supporting-board 11, and the mote-board 10 is extended downward 100

at an inclination in advance of the supporting-board to form an inclined front portion or chute 14, arranged to receive the falling motes, nap, sand, and other heavy matter removed 5 from the saws by the rotary brush-cylinder, and the said inclined front portion or chute is adapted to direct such matter into the seed-conveyer. (Not shown.)

The gin frame or stand is provided at its 10 upper portion with a front opening 15, and the cotton-seed is discharged through the same in the usual manner, a cotton-seed conveyer of the ordinary construction being employed for carrying off the cotton-seed, motes, nap, 15 and sand. The motes, nap, and sand are discharged through a lower opening 16, located at the lower or front end of the inclined portion or chute 14 of the mote-board 9. The inclined front portion or chute is curved, as 20 shown, and it extends from the front portion of the supporting-board 11 to the front of the gin frame or stand at the bottom of the opening 16, and it thereby closes the gin stand or frame at the bottom. By closing the gin stand 25 or frame at the bottom a direct vertical draft from the bottom of the gin-frame through the space between the supporting-board 11 and the front of the frame to the gin-saws is prevented. A direct vertical draft from the bottom 30 of the gin-frame to the gin-saws has been found exceedingly disadvantageous, as it interferes with the operation of the rotary brush-cylinder in removing the lint and separating the mote, nap, and sand from the same. It 35 has been found by experience that when the mote-board is moved forward sufficiently to prevent a direct upward draft the brush will 40 not separate the motes and trash from the lint and throw them downward, but will carry all along with the lint into the lint-room. If the 45 front edge of the mote-board is pushed back sufficiently to permit a proper operation of the brush, space is left open and a direct vertical draft results and prevents the motes and trash from being separated from the lint and often causing the brush to drop the lint with the motes and waste the former. The inclined flexible apron or chute forms practically an inclined passage from the front opening 16 to the rear passage or flue 8. The 50 motes and trash are thrown downwardly upon the inclined apron or chute, at the top thereof, and they slide down the apron or chute and are discharged into the cotton-seed conveyer. 55 The supporting-board 11 is mounted in horizontal guides or ways 17, formed by upper and lower horizontal cleats or bars, as clearly shown in Fig. 1 of the drawings, and it is capable of adjustment and is adapted to be moved 60 backward or forward to vary the size of the opening or space 12 between the upper end of the inclined portion or chute of the mote-board and the front of the gin stand or frame to regulate the draft and to effect a proper 65 discharge of the motes, nap, and sand.

The inclined portion or chute 14 forms a flexible apron and is adapted to be readily bent or shaped to accommodate itself to the adjustment of the upper portion of the mote-board, and after a proper adjustment has been obtained the lower edge of the inclined portion or chute may be secured to the front of the gin-frame at the bottom of the opening 16 by suitable fastening devices. The gin frame or stand is curved at the bottom of the opening 75 16 to form a concaved seat for the reception of the curved front portion of the mote-board. The inclined chute or apron prevents the motes, nap, and sand from falling beneath the gin frame or stand and endangering the cotton-gin from fire and necessitating their removal from beneath the gin frame or stand by hand, which operation frequently results in the loss of a hand or an arm.

The lower opening 16 of the front of the 85 frame may, if desired, be partly closed by a board or any other suitable means for preventing the motes, nap, sand, and other heavy matter from entering the seed-conveyer when it is desired to obtain absolutely clean seed. 90

What I claim is—

1. In a cotton-gin, the combination with a frame or stand provided at the front with an opening, gin-saws, and a rotary brush-cylinder, of a mote-board comprising an approximately 95 horizontal portion located beneath the brush-cylinder, and an inclined portion extending downward at the front of the horizontal portion to the said opening and closing the space at the bottom of the frame or stand and forming a chute, substantially as described.

2. In a cotton-gin, the combination with a frame or stand provided at the front with an opening, of a mote-board comprising an upper approximately horizontal portion, and an inclined portion extending downward from the horizontal portion to the said opening, and forming a chute and closing the space at the bottom of the frame or stand, substantially as described.

3. In a cotton-gin, the combination with a frame or stand provided with an opening, of a mote-board consisting of an upper portion, and an inclined portion extending from the upper portion to the opening to form a chute 115 and to close the space at the bottom of the frame or stand, substantially as described.

4. In a cotton-gin, the combination with a frame or stand provided with an opening, of a mote-board constructed of flexible material 120 and consisting of an upper approximately horizontal portion, and a curved front portion arranged at an inclination and extending downward to the opening to form a chute, substantially as described.

5. In a cotton-gin, the combination with a frame or stand having an opening, of a mote-board comprising an upper adjustable portion, and an inclined flexible apron extending from the adjustable portion to the opening, to form 130

a chute and to close the space at the bottom of the frame or stand, substantially as described.

6. In a cotton-gin, the combination with a frame or stand having an opening and provided with ways, of an adjustable supporting-board arranged in the ways, and a mote-board constructed of flexible material, and consisting of an upper portion carried by the supporting-board, and an inclined portion extending therefrom to the said opening and forming a flexible apron, substantially as described.

7. In a cotton-gin, the combination with the gin saws, ribs, and brush-cylinder, of a mote-board comprising a rigid section, and a flexible apron or chute.

8. In a cotton-gin, an adjustable mote-board having at one end a flexible apron extension depending therefrom.

9. In a cotton-gin, the combination with the gin-stand having an opening at the front below the gin-saws, of a mote-board having an apron or chute communicating with the interior of the gin and discharging through the said opening.

10. In a cotton-gin, the combination with the gin saws, ribs, and brush-cylinder, of an adjustable mote-board having an apron or chute communicating respectively with the interior and exterior of the gin.

11. In a cotton-gin, the combination with the

gin saws, ribs, and brush-cylinder, of an adjustable mote-board comprising an upper rigid portion adjustable toward and away from the front of the gin and provided with an apron or chute.

12. In a cotton-gin, the combination with the saws, gin-ribs, and brush-cylinder, of a mote-board partially closing the space below the saws and brush-cylinder, and having an apron or chute which communicates with the exterior of the stand.

13. In a cotton-gin, the combination with the saws, gin-ribs, and brush-cylinder, of a mote-board comprising a relatively rigid portion, and a flexible apron or chute extension.

14. In a cotton-gin, the combination with the saws, gin-ribs, and brush-cylinder, of a mote-board comprising a relatively rigid portion partially closing the space at the bottom of the saws and brush-cylinder, and an apron or chute fitted in the space between the said rigid portion and the front of the gin-stand, and communicating at its outer end with the exterior of said stand, for the purpose described.

In testimony that I claim the foregoing as my own I have hereto affixed my signature in the presence of two witnesses.

CLEMENS G. BODUNGEN.
